UNITED STATES PATENT OFFICE.

CHARLES WIRT, OF CHICAGO, ILLINOIS.

DESIGN FOR AN INSULATOR-BRACKET.

SPECIFICATION forming part of Design No. 21,378, dated March 8, 1892.

Application filed January 4, 1892. Serial No. 417,017. Term of patent 3½ years.

To all whom it may concern:

Be it known that I, CHARLES WIRT, a citizen of the United States, residing at Chicago, in the county of Cook and State of Illinois, 5 have invented and produced a new and original Design for Brackets for Electric Wires, of which the following is a specification.

My design relates to brackets, and of it the following is a specification, reference being 10 had to the accompanying drawings, forming part thereof.

Figure 1 is a side view of my bracket. Fig. 2 is a plan view thereof.

Like parts are indicated by the same letters 15 in both figures.

A is a cylindrical part; B B, laterally-projecting arms thereon; D D, cylindrical portions at the ends of the arms, and C C flanges

on top and bottom of the arm and extending from one cylindrical portion to the other, and 20 F a cylindrical portion between the flanges and in line with the cylindrical part A.

I claim—

The design for an electrical insulator-bracket, the same comprising the cylindrical supporting-standard, flat arms projecting in opposite directions therefrom, cylindrical pieces, one at the outer end of each arm, flat plates above and below the arms and uniting the two outer cylindrical pieces, and the cylindrical portion between the two flat plates, substantially as shown and described.

CHARLES WIRT.

In presence of—

FRANCIS W. PARKER,
VIRGINIA WILLEY.
